UNITED STATES PATENT OFFICE.

BENJAMIN EUGENE PARRISH AND SOLOMON STAGE, OF MINERAL WELLS, TEXAS.

BIT-HOIST.

1,294,153.

Specification of Letters Patent.

Patented Feb. 11, 1919.

Application filed June 22, 1918. Serial No. 241,382.

To all whom it may concern:

Be it known that we, BENJAMIN E. PARRISH and SOLOMON STAGE, citizens of the United States, residing at Mineral Wells, in 5 the county of Palo Pinto and State of Texas, have invented new and useful Improvements in Bit-Hoists, of which the following is a specification.

This invention relates to new and useful 10 improvements in bit or drill hoists and the principal object of the invention is to provide means for handling bits or drills of well boring machines and the like.

By our invention the bit or drill may be 15 easily removed from the drilling machine and transported to the forge and easily handled in the operations of dressing the bit, or the machine may be used for placing the drills in their racks or in raising the 20 drills off the floor or ground.

Another object of the invention is to provide a device of this character which is simple and durable in construction, reliable and efficient in operation and one which can 25 be manufactured and placed upon the market at a minimum cost.

The invention also consists in certain other features of construction and in the combination and arrangement of the several 30 parts, to be hereinafter fully described, illustrated in the accompanying drawings and specifically pointed out in the appended claims.

In describing our invention in detail, reference will be had to the accompanying 35 drawings wherein like characters denote like or corresponding parts throughout the several views, and in which:—

Figure 1 is a front view of the machine. 40 Fig. 2 is a longitudinal section.

Fig. 3 is a top view.

Fig. 4 is a transverse section through the swiveled ring.

Fig. 5 is a section on line 5—5 of Fig. 4. 45 Fig. 6 is a detail view.

In these views 1 indicates the platform mounted on the wheels 2, some of which may be caster wheels to permit the platform to be easily steered. The platform is provided 50 with a centrally located opening 3 which receives the stub shaft 4 carried by a cross head 5. If desired, suitable anti-friction bearings may be located between the platform and the part carrying the shaft to act 55 as a thrust bearing. In this manner the cross head may be revolved above the plat-

form. At each end of the cross head is mounted an upright 6 of tubular shape and provided with a longitudinal slot 7 which communicates with the bore of said upright. 60

A screw shaft 8 is mounted in each upright with its lower end projecting through the end of the upright and said lower end is provided with a beveled gear 9 which meshes with like gears 10 secured to the 65 ends of a shaft 11 passing through the cross head. 12 is a traveling block engaging each of the uprights and provided with a part extending within the slot 7 and engaging the screw threaded shaft. In this way when 70 the shafts are revolved the blocks will be moved vertically along the uprights. A ring 13 is swiveled to said blocks at diametrically opposite points by means of bolts or pins and a carrying member 14 has a 75 circumferential groove 15 in which said ring fits. Said carrying member is provided with a central opening 16 which passes through one edge of said member and the ring is provided with a slot 17 of substantially the same width as said opening. 80 The upper face of the carrying member is provided with lugs 18 having screw threaded openings therein through which pass large set screws 19 having supporting heads 85 20 swiveled to their inner ends. The screw shafts are operated by means of a crank 21 carried by a shaft 22 supported in a bracket 23 connected with one of the uprights and said shaft is geared to a second shaft 24 90 which is suitably connected with one of the gears 9, so that when the crank 21 is rotated both of the screw shafts 8 will be revolved to move the ring and the carrying member 95 vertically on the upright.

The operation of the machine is as follows:—

The carriage or platform is moved close to the tool hanging in the derrick or drilling machine and the carrying member is turned 100 until its opening coincides with the slot in the ring so that the tool may pass into said opening. The set screws are turned until the swiveled heads thereon will enter the water grooves A formed in the tool. The 105 set screws are then turned to clamp the tool between said heads. The carrying member is then revolved on the ring to unscrew the tool from the machine. The ring is then lowered by turning the crank until the ring 110 with the tool in the carrying member is near the lower ends of the uprights, it being

understood that the tool is rocked until it assumes a horizontal position when the ring is at the lower part of its movement, the ring turning on its pivots to permit the tool to 5 assume its horizontal position. The platform or carriage is then rolled to the forge and the device may be manipulated to place the end of the tool in the forge. If desired a shield may be placed on the machine to 10 protect the parts from the heat of the forge. After the tool has become sufficiently heated the carriage or platform is moved over to the anvil to permit the end of the tool to be dressed. The swiveled ring and carrying 15 member will permit said tool to be turned in all directions to permit the proper dressing of the point. After this is done the tool may be reheated and then lifted to a vertical position to permit the point being placed in the tub of water. After this 20 is done the tool may be returned to the drilling machine and replaced therein or it may be taken to the rack. The device may be used for picking up tools by simply hitching 25 a rope around the tool and around the carrying member and raising the parts by the crank.

It is thought from the foregoing description that the advantages and novel features 30 of our invention will be readily apparent.

We desire it to be understood that we may make changes in the construction and in the combination and arrangement of the several parts, provided that such changes 35 fall within the scope of the appended claims.

What we claim is:—

1. A hoist of the class described comprising a carriage, a cross head swiveled thereon, uprights carried by the head, a ring carried by the uprights, means for moving said 40

ring vertically on said uprights and means for rotatably clamping the tool in said ring.

2. A hoist of the class described comprising a carriage, a cross head swiveled thereon, uprights carried by the cross head, traveling blocks on said uprights, means for moving said blocks vertically, a ring swiveled on said blocks, a carrying member rotatably supported on said ring and tool clamping means carried by said member. 45

3. A hoist of the class described comprising a carriage, a cross head swiveled thereon, a pair of tubular uprights carried by the cross head and having slots therein, a screw shaft in each upright, means for rotating 55 said screw shafts, a block on each upright and having a part engaging the screw shaft, a ring pivoted to said blocks, a carrying member having a circumferential groove in which the ring fits, and means for clamping 60 the tool to said member.

4. A hoist of the class described comprising a carriage, a cross head swiveled thereon, uprights carried by said cross head, screw shafts in said uprights, means for 65 rotating said shafts, a traveling block on each upright having a portion engaging with said screw shafts, a slotted ring pivoted to said blocks, a carrying member having a central opening adapted to coincide with 70 the slot in the ring and having a circumferential groove for receiving the ring, lugs on said member, set screws carried by said lugs and a swiveled head carried by each screw for engaging the tool. 75

In testimony whereof we affix our signatures.

BENJAMIN EUGENE PARRISH.
SOLOMON STAGE.
